UNITED STATES PATENT OFFICE

2,253,233

SEWING MACHINE

Joseph Gouldbourn and Thomas Aubrey Kestell,
Leicester, England, assignors to United Shoe
Machinery Corporation, Borough of Flemington,
N. J., a corporation of New Jersey

Application May 18, 1939, Serial No. 274,394
In Great Britain June 15, 1938

19 Claims. (Cl. 112—35)

This invention is concerned with improvements in or relating to sewing machines and is particularly, but by no means exclusively, concerned with curved hooked needle chainstitch sewing machines such as are particularly adapted for sewing the uppers and welts of boots or shoes (hereinafter referred to generically as shoes) of the so-called welted type, to lips or ribs on insoles secured on the bottoms of lasts within the uppers.

An example of such welt-sewing machines is disclosed in the patent to Eppler No. 1,108,560 dated August 25, 1914.

While welt sewing machines of the kind at present in most general use are able, when run at a speed in the neighborhood of 600 R. P. M., to give results which are acceptable to shoe manufacturers yet we have observed that such machines are generally unable to stitch the upper, welt, and insole of a shoe as firmly together around the toe of the shoe as around the sides of the latter and, moreover, the particular arrangement of intermittent work-feeding instrumentalities which such machines make use of is not able consistently to ensure that the work is fed even distances between successive stitches, any unevenness in the stitch length producing an uneven appearance in the sewn seam and militating against the best results being obtained from the sewing operation. Moreover, such machines as just referred to are unsuited for high speed operation since, inter alia, the intermittently acting work-feeding mechanism, if run at a high speed in the neighborhood of 900 R. P. M., not only imparts rapid and jerky feeding movements to the work which are likely to vary in length during successive sewing cycles, but also suffers from such rapidly developing mechanical wear or strain as speedily to render it unreliable.

It is one of the several objects of the present invention to provide a novel and improved welt-sewing machine which shall be capable of producing stitches of substantially uniform tightness and of substantially uniform length all round the shoe forwardly of the heel breast line and shall contain work-feeding mechanism able to feed the work in a very smooth and continuous manner without undue vibration and without causing strain to develop in the machine even if run at high speed, such mechanism moreover allowing the operator to manipulate the shoe with relative ease during its passage past the sewing point.

With this one of the several objects in mind, a particular illustrative embodiment of the pres-

ent invention hereinafter described includes, with a view to ensuring the formation of uniformly tight stitches around the toe as well as along the sides of the shoe, needle loop deflector and thread finger mechanism similar in many respects to those disclosed in applicants' pending application Serial No. 150,728 filed June 28, 1937, and with these mechanisms is combined a work-feeding mechanism arranged to feed the work continuously (or substantially continuously) during the whole of a machine cycle, as opposed to feeding it intermittently during part only of the cycle. The illustrative embodiment of work feeding mechanism is novel and comprises mechanism for causing the needle, awl, and channel guide (which members cooperate in the continuous feed of the work) to operate in such relative time sequence and at such relative speeds as, inter alia, to ensure that the channel guide is effective in continuing the movement of the work both when the awl is leaving the work and the needle is entering it and vice versa, and as to ensure that, preparatory to the needle actually entering the work, the awl will have been feeding the work along at a faster speed than that at which the needle moves in the direction of work feed when it has entered the work, thus tending to relieve the needle of strain exerted on it in feeding the work. The illustrative embodiment of the several features of the present invention also includes an arrangement whereby the needle and awl are both caused to enter the work from one and the same side of the insole ribs or lips and whereby the channel guide is arranged, by engagement with the work at the other side of the insole ribs or lips, to give very effective support to the work against the piercing action of the awl and needle; and an arrangement whereby, in spite of their movements to and fro along the line of work feed, the needle, awl, and channel guide at all times lie relatively close together laterally of the machine to facilitate the necessary turning of the shoe by the operator as the sewing proceeds around the toe.

In the said illustrative embodiment hereinafter described both the awl and needle are arranged to enter the work from the rear side of the channel lips and the channel guide is arranged to engage the channel at the other or forward side of the lips, the needle being arranged to enter the hole made in the work by the awl just after the awl leaves the work. The awl and needle are moved to and fro laterally once in each cycle of the machine to feed the shoe when in engagement therewith and the channel guide is moved

to and fro twice in each cycle of the machine, and is arranged to continue the feed of the work at those two relatively short times in the cycle when neither the awl or the needle is in engagement with the work. The channel guide is moved in a direction (i. e. towards the right) opposite to that in which the work is fed at that stage when the needle is moving back towards the right and, after the needle, channel guide, and awl have thereafter moved in company towards the left to carry the work a further step through the machine, the channel guide is given a further return movement towards the right at a later stage in the cycle when the awl moves towards the right.

As above indicated, the arrangement is such that the two movements of the channel guide towards the left (which occur after the completion of the back-feeding movements of the needle and awl respectively) occur while the needle is withdrawing from the work and the awl is preparing to enter it and vice versa. Since the channel guide, the needle, and the awl are then moving in company towards the left, the leftward movements of the channel guide assist in ensuring the even continuance of the feeding movement of the work during those short periods which intervene between the complete withdrawal of the needle or awl from the work and the entry of the awl or needle into it and when the awl, or needle, has sufficiently entered the work to enable it to exercise a more or less positive feeding action thereon, the channel guide is moved back towards the right.

Thus the two lateral movements of the channel guide need only be of a relatively short duration and, owing to this fact the channel guide is enabled to lie comparatively close to the needle and awl, considered laterally of the machine, at all times in the machine cycle and this close grouping of said three instrumentalities facilitates the turning of the work during the sewing around the toe without danger of the channel guide distorting the insole lips.

Moreover, the sub-division of the work feed between the needle, awl, and channel guide in the particular manner indicated, makes for a very smooth and even passage of the work through the machine and relieves the operator of any undue effort in controlling the work during the sewing therearound.

As will hereinafter become more clear, the various mechanisms of the present illustrative embodiment which serve to impart their work-feeding movements to the needle, awl, and channel guide are such as are likely to run at high speeds with relative freedom from vibration and wear.

The channel guide is arranged more or less directly in front of the awl when the latter commences to strike into the work and thus affords very effective support to the insole lips at that time. The awl does not strike right through the insole lips and strike the channel guide, but moves across to the left away from behind the channel guide, while its point is projecting into the work, until it comes into line with the needle at the left of the channel guide. Because the awl is arranged to strike into the work from the rear while the insole lips are supported by the channel guide, the awl is able to pierce through the layers of upper material, the welt, and almost completely through the insole lips, thus leaving very little work piercing duty to be performed by the needle and consequently reducing

the possibility of needle breakage—a result which could hardly be expected if the awl were caused to pierce the work from the forward side, as is at present usual, since the parts to be sewn together are not supported, at the rear by any firm abutment in the region of the sewing point.

Since the needle is a more slender, and therefore weaker, member than the awl, it is desirable to guard against a possibility for the needle to be bent or deflected out of its proper path at a stage in the machine cycle when it is serving as the sole work feeding member. To this end, the awl of the present illustrative machine (which is travelling with the work just prior to the entry of the needle into it) is caused automatically to move the work towards the left a little faster than the needle is moving in that direction just before the substitution of the needle for the awl in the work takes place, thus bringing about the result that the increased momentum in the work will, at the time the needle enters it, tend to eliminate any tendency that might otherwise be present for the work, by its resistance to movement, to bend the needle when the latter commences its feeding movement. Moreover, the awl is arranged to feed the work through a greater distance in each cycle than the needle.

The above and other of the various objects of the invention will become clear from the description (with reference to the accompanying drawings) which is now given, by way of example and not of limitation, of the said illustrative example, and the several features of the invention will be found set out in the appended claims.

In the accompanying drawings:

Figures 1 and 2, taken together, illustrate in right hand side elevation, the upper part of a chainstitch welt shoe sewing machine in which an embodiment of the several features of the invention is included; Figure 3 is a detail view of the looper; Figure 4 is a left hand side elevation of the said mechanism; Figure 5 is a plan view, partly in section, of needle and channel guide feeding mechanism of the said illustrative embodiment; Figure 6 is a front elevation, partly in section, of part of an awl feeding mechanism of the said illustrative embodiment; Figure 7 is a plan view of part of the mechanism shown in Figure 6; Figure 8 is a plan view, partly in section, of needle, awl and channel guide feeding mechanism of the illustrative embodiment; Figure 9 is a right hand side elevation of a channel guide supporting and actuating mechanism of the illustrative embodiment; Figure 10 is a right hand side elevation of welt guide locking mechanism of the illustrative embodiment; Figure 11 is a section on the line XI—XI in Figure 10; Figure 12 is a section on the line XII—XII of Figure 10; Figure 13 is a front elevation of a thread deflector and its actuating mechanism of the illustrative embodiment; Figure 14 is a right hand side elevation of a mechanism for moving the thread finger forwardly or rearwardly with the welt guide of the illustrative embodiment; Figure 15 is a front elevation of a looper actuating mechanism of the illustrative embodiment; Figure 16 is a front elevation showing the relative positions of the stitch-forming and work feeding devices of the illustrative embodiment in the stopping position of the machine; Figure 17 shows the relative positions of these parts after a cam shaft of the machine has rotated through fifty-five degrees from its stopping po-

sition; Figure 18 shows the relative positions of these parts when the cam shaft has rotated through a further one hundred degrees; Figure 19 shows the relative positions of the stitch-forming and work feeding devices when the cam shaft has rotated through a further one hundred degrees; Figure 20 is a right hand side elevation showing the stitch-forming and work feeding devices in the same relative positions in which they are shown in Figure 17; Figures 21 and 22 show in side elevation these parts in the same relative positions in which they are shown in Figures 18 and 19 respectively; Figure 23 is a diagram indicating the relative timing of the operating parts of the machine.

The illustrative machine in which said illustrative embodiment is included is, except as will hereinafter appear, of the same general character as that disclosed in the patent to Eppler No. 1,108,560 above referred to. In the illustrative machine, however, the curved awl 1 and the curved hooked needle 3 both move forwardly into engagement with the work, i. e., they both enter the work at the same side thereof.

In the illustrative machine, the work is fed continuously or substantially so by the cooperation of the awl, needle, and a channel guide 5 of the machine, these parts being so operated that one or more are continually in engagement with and feeding the work.

The needle 3 of the illustrative machine is secured in a needle carrier 7 which is oscillated about a horizontal axis extending laterally of the machine and is arranged to be moved to and fro laterally of the machine. The awl 1 is secured in the lower end of an arm 11 which is oscillated about a horizontal axis extending laterally of the machine and is also moved to and fro laterally of the machine. The axis of the awl carrying arm is higher than and somewhat forwardly of the axis of the needle carrier 7. The curved paths of the needle and awl are so arranged that as the awl is being moved rearwardly out of and away from the work, the needle is advancing towards and into the hole in the work just left by the awl along a path just above the awl.

The needle carrier 7 has extending from it towards the right a horizontal sleeve 15 (Figure 5) which is rotatably and slidably mounted in a bearing 17 on a downwardly and forwardly projecting arm of a bracket 19, Figs. 1, 5 and 8, secured on the front portion of a head 21 of the machine.

The needle carrier 7 has pivotally connected to it by a universal coupling the forward end of a rearwardly extending link 23 (Figs. 1 and 2). The rear end of the link 23 is pivotally connected by a universal connection to the forward end of a cam lever 25 which, at its rear end is pivoted on a horizontal shaft 21 extending laterally of the machine and secured in the head 21 of the machine at the rear of a horizontal cam shaft 29 of the machine which extends laterally thereof and is rotatably mounted in the head 21. The cam lever 25 has extending laterally from it between its ends a cam roll 31 which enters a cam groove in a cam secured on the cam shaft 29.

The awl carrying arm 11 extends downwardly and rearwardly from the hub of an awl lever 33 which has extending towards the right from it a stem 35 (Figure 6) which is rotatably and slidably supported by a bracket 37 secured to the underside of the bracket 19, Figs. 1 and 8.

The awl lever 33 has an upwardly and rearwardly extending arm 39 (Figure 1) the upper end of which is pivotally connected by a universal coupling to the rear end of a forwardly and upwardly extending link 41. The forward end of the latter link is pivotally connected by a universal coupling to the lower end of one arm 43 of a bell-crank lever 45. The bell-crank lever 45 is pivoted on a horizontal shaft 47 extending laterally of the machine secured in the machine head 21. Another arm 49 of the bell-crank lever 45 extends rearwardly and has extending laterally from it a cam roll 51 which engages in a cam groove in a cam secured on the aforesaid cam shaft 29 of the machine.

The needle carrier 7 has extending to the left from it a horizontal sleeve 53 (Figure 5) on which is mounted so as to rotate to a limited extent relatively to the sleeve a needle guide sleeve 55 having on its right hand end a needle guide 57. The needle guide sleeve 55 is rotatably and slidably mounted in a needle guide driving sleeve 59 which is rotatably mounted in a bearing 61 on a bracket 63 secured on the head of the machine at the left of the first mentioned bracket 19. The needle guide driving sleeve 59 has on its left hand end a gear segment 65 which is engaged by a gear segment 67 formed on an arm 69 which is pivoted on a horizontal shaft 71 extending laterally of the machine. The arm 69 has extending from it a sleeve through which the shaft passes and the sleeve has adjustably secured on it an arm 73 which carries a cam roll 75 which engages a cam groove in a cam on the cam shaft 29. The arms 69 and 73 may be adjusted relatively about the shaft 71 to adjust the position of the needle guide 57 relatively to the point of the needle.

The right hand end of the needle guide driving sleeve 59 has extending from it a projection 77 (Figure 4) which engages in a recess formed in a flange 79 on the right hand end of the needle guide sleeve 55 to drive the needle guide sleeve. The flange on the needle guide sleeve has extending downwardly from it an arm to which is secured the needle guide 57.

The sleeves 15 and 53 aforementioned on the needle carrier 7 are bored axially and have passing axially through them a rod 81 which is slightly smaller in diameter than the bore in the sleeves. The rod 81 at its right hand end has formed on it a head 83. The right hand end face of the right hand sleeve 15 on the needle carrier 7 is slightly rounded and the left-hand end face of the head 83 on the rod 81 is slightly concave and engages the rounded end of the sleeve. The left hand end of the rod 81 has on it a washer 85 having a slightly concave right hand end face which engages the left hand slightly rounded end faces of the left hand sleeve 53 on the needle carrier 7 and needle guide sleeve 55. The rod 81 has on its left hand end a nut and locknut 87 which are adjusted so as to allow the needle carrier 7 to oscillate relatively to the rod 81 and to allow slight lateral movement of the rod 81 relatively to the sleeves, the concave and rounded faces on the sleeves, washer and head of the rod assisting in this lateral movement taking place. The head 83 on the right hand end of the rod 81 is forked and extending across the fork is a vertical pin 88 which pivotally connects the fork to the forward end of an arm 89 of a needle feed lever 99 which is pivoted on a vertical spindle 101 secured in the head 21 of the machine. The needle feed lever 99 has

another arm 103 which extends from the hub of the lever towards the right and somewhat rearwardly.

The right hand end of the latter arm 103 has pivotally connected to it by a vertical pin 105 the forward ends of a pair of parallel links 107, one above and the other below the end of the arm. The rear ends of the links 107 are pivotally connected by a vertical pin 109 to the forward end of a single link 111 (Figure 8), positioned between the rear ends of the pair of links 107, which extends rearwardly and to the right and the rear ends of the links 107 are also pivotally connected by the pin 109 to the left hand ends of a second pair of links 113, one above and one below the rear ends of the first pair of links 107. The single link 111 is pivoted at its rear end to the forward end of one arm 115 (Figure 8) of a cam lever 117 which is pivoted on a vertical spindle 119 secured in the machine head 21 rearward of the cam shaft 29. Another arm 121 of the cam lever 119 extends forwardly from its hub beneath the cam shaft 29 and carries at its forward end an upwardly extending cam roll 123 which enters a cam groove in a cam on the cam shaft. The right hand ends of the second pair of links 113 are pivoted on a vertical spindle 125 (Figure 5) which is secured in the right hand end of a yoke member 127, the left hand end of which has extending upwardly and downwardly from it pins 129 which are rotatably mounted in the machine head. The yoke member 127 is normally secured to the head of the machine but may be adjusted about the axis of vertical pins 129 extending upwardly and downwardly from the yoke member to adjust the axis about which the second pair of links 113 are moved by the cam lever 117 and so vary the path of movement of the pivot 109 connecting the two pairs of links 113, 107 and the single link 111 so as to adjust the amount of feed movement imparted to the needle. The aforesaid vertical spindle 125 on the yoke member 127 extends downwardly from the member and passes through a curved slot 131 in a portion 133 of the machine frame which slot is concentric to the axis about which the yoke member is adjusted. The lower end of the spindle is threaded and has on it a nut 135 (Figs. 1 and 2) by means of which the yoke member may be secured to the machine frame. The position in the machine of the pins 129 on the yoke member 127 is such that at a certain time in the cycle of the machine the axis of the pivot 109 connecting the two pairs of links 107, 113 and single link 111 is in vertical alignment with the axis of the pins 129 on the yoke member. The said axes are in alignment when the awl is moving rearwardly out of and away from the work and the needle is moving forwardly and into the hole in the work made by the awl and the centre lines of the needle and awl are in the same vertical plane. Adjustment of the yoke member about the axis of the pins 129 does not therefore alter the relative positions of the needle and awl laterally of the machine at the time when the awl is moving away from the work and the needle is moving towards the work.

The stem 35 on the awl lever 33 (Figure 6) passes through a sleeve 137, in which it can oscillate, which is slidingly mounted in the bracket 37 which is secured to the underside of the bracket 19. The bracket 37 is secured to the bracket 19 by bolts 139 (Figure 7) which pass through slots 141 in the bracket 37 which allow

the bracket 37 to be adjusted on the bracket 19 so that the path of the awl is parallel to the path of the needle or is at an angle thereto. If the awl is arranged to move in a path which is at an angle to the path of the needle, the awl point is moved forwardly and towards the needle path from the right thereof so that if the work is turned, for example, in sewing around the toe of a shoe, the hole in the work made by the awl will be brought more or less into line with the path of the needle. The right hand end of the stem 35 on the awl lever 33 is reduced in diameter and the reduced portion is threaded and has on it a washer 143 and nut 145. The washer 143 engages the right hand end of the sleeve 137 and the hub of the lever engages the left hand end of the sleeve. The arrangement being such that the awl lever 33 moves with the sleeve 137 laterally of the machine and oscillates relatively to the sleeve. The sleeve 137 has extending upwardly from it near the right hand end an eccentric stud 147 on which is pivoted the right hand end of a horizontal link 149 extending laterally of the machine. The left hand end of the link 149 is pivotally connected by a vertical pin 151 to the forward end of one arm 153 of an awl feed lever 155 which is pivoted on the same vertical spindle 101 as the needle feed lever 99. The awl feed lever 155 has extending towards the right and somewhat rearwardly from its hub an arm 157 which has pivoted to it the forward ends of a pair of parallel links 159 one above and the other below the arm. The rear ends of the pair of links 159 have pivoted to them by a vertical pin 161 a second pair of parallel links 163, one above and the other below the first pair 159, and the forward end of a single link 165 positioned between the rear ends of the first pair of links 159. The second pair of links 163 extend towards the right and their right hand ends are pivoted on the same vertical spindle 125 carried by the yoke member 127 as the second pair of links 113 associated with the needle feed mechanism. The rear end of the single link 165 is pivotally connected by a vertical pin 167 to one arm 169 of a cam lever 171 which has another arm 173 extending beneath the cam shaft 29 and carrying an upwardly extending cam roll 175 which enters a cam groove in a cam on the cam shaft. The mechanism for moving the awl to and fro in the direction of feed is similar to the mechanism for so moving the needle and, if the yoke member 127 is adjusted as aforesaid, the feed movement of the awl is adjusted simultaneously with the adjustment of the feed movement of the needle. By means of the eccentric stud 147, the awl may be adjusted laterally of the machine to bring it into correct relationship to the needle when assembling the parts. The needle moves in the direction of work feed during about 280 degrees of each machine cycle and moves in the opposite direction or returns during about 80 degrees of the cycle. The awl moves in the direction of feed during about 260 degrees of the cycle and returns during about 100 degrees of the cycle. The awl is caused to feed the work a somewhat greater distance than the needle and, when the awl is feeding the work, its feeding movement is somewhat quicker than the feeding movement of the needle when the latter is about to feed the work, with the result that the awl imparts a momentum to the work which enables the needle to take up the feed without undue lateral strain thereon.

The channel guide 5 is secured on a vertical face formed on the front of an arm 177 (Figure 9) of a channel guide lever 179 which arm 177 extends rearwardly from its forward end and the lever 179 is pivoted on an eccentric portion 181 of a vertical shaft 183 secured in the machine head. By rotating the shaft 183, the channel guide may be adjusted forwardly or rearwardly in the machine. The channel guide 5 is secured to the front face of the arm 177 by a clamp screw 185 which passes through a vertical slot in the channel guide and the channel guide may be adjusted heightwise on the arm 177 by an eccentric 187 which is rotatably mounted in the arm and engages a groove extending across the rear face of the channel guide. The channel guide lever 179 has a rearwardly extending horizontal arm 189 to the rear end of which is pivoted by a vertical pin 191 a two-armed lever 193, one arm of which extends forwardly and the other rearwardly from the pin 191. The arms of the two-armed lever have pivotally connected to them by vertical pins 195, 197 a pair of parallel horizontal links 199, 201 of equal length which extend towards the right. The right hand end of the rear link 201 is pivotally connected by a vertical pin 203 to the rear end of an arm 205 extending rearwardly from the aforesaid awl feed lever 155, which arm lies above the last-mentioned arm 205 on the needle feed lever. The right hand end of the front link 199 is pivotally connected by a vertical pin 207 to the rear end of an arm 209 which extends rearwardly from the aforesaid awl feed lever 155, which arm lies above the last-mentioned arm 205 on the needle feed lever. The channel guide 5 therefore receives its to and fro movement along the line of feed from the needle and awl feed mechanisms. The vertical shaft 183 on which the channel guide lever 179 is pivoted and the vertical spindle 101 on which the awl and needle feed levers 155, 99 are pivoted are positioned side by side in the machine the same distance rearwardly from the line of feed which extends from right to left of the machine and the links 199, 201 which connect the two-armed lever 193 on the channel guide lever 179 and the awl and needle feed levers are both equal in length to the distance apart of the shaft 183 and spindle 101. When the rearwardly extending arms 209, 205 of the awl and needle feed levers are swung towards the right, viewed from above, together to cause both the awl and needle to move in the direction of feed, the channel guide 5 will also be moved in the direction of feed with them.

If, however, either the awl or needle lever remains stationary while the other is moving, the channel guide will be moved only half as far as the awl or needle whichever is being moved, and if either the awl or needle feed lever is being moved in a direction to feed the work and the other is being moved in the opposite direction then, depending on the direction of movement of the awl and needle feed levers, the channel guide lever may be moving in a direction to feed the work or in the opposite direction.

The channel guide is positioned in front of the awl when the latter moves forwardly into engagement with the work, and the work is therefore well supported during the work penetrating movement of the awl. The awl, when feeding the work towards the left, moves from behind the channel guide to a position just at the left of the latter into a position where the needle can enter the hole in the work made by the awl and the needle, awl and channel guide are po-

sitioned, considered laterally of the machine, comparatively close together and do not interfere with the turning of the shoe when sewing is being performed around the toe or other curved portions thereof.

Assuming the illustrative machine to be in operation to sew a seam and the sewing instrumentalities to have reached once more the positions which they occupied when the machine came to rest, the awl and needle are both out of the work and their center lines are in the same vertical plane. The needle is moving forwardly towards the work and the awl is moving rearwardly away from the work. The awl, needle and channel guide are all moving in the direction of feed, the work being held against the channel guide by the operator which is feeding the work. The awl, the timing of which is indicated by the line A in the accompanying diagram, reaches its most 10 rearward position, indicated by the letter *a* in line A, when the cam shaft has rotated through about 25 degrees from its starting position and the needle, the timing of which is indicated by the line B in the diagram, reaches its most forward position, indicated by the letter *a* in line B, when the cam shaft has rotated through about 50 degrees from its starting position. The awl remains in its most rearward position while the cam shaft rotates through about a further 90 degrees when it begins to move forwardly into engagement with the work and reaches its most forward position when the cam shaft has rotated through about 180 degrees from its starting position. The awl dwells in its most forward position while the cam shaft rotates through about 150 degrees when it begins to move rearwardly out of and away from the work. The needle remains in its most forward position while the cam shaft rotates through about 95 degrees and then commences to move rearwardly and reaches its fully retracted position when the cam shaft has rotated through about 245 degrees from its starting position. The needle immediately begins to move forward slightly and at the same time is moved laterally in the opposite direction to the direction of work feed. The slight forward movement of the needle continues during about 100 degrees of rotation of the cam shaft when the needle begins to move rapidly forwardly towards the work. The needle, when in its rearward position, has drawn a loop of thread through the work and the slight forward movement of the needle as it is moved laterally prevents undesirable strain being placed on the thread.

The channel guide does not move towards or from the work during normal operation of the machine but may be moved forwardly as the machine stops so as to allow work to be removed from and presented to the machine.

The needle continues to move in the direction of feed, see the line C in the diagram, until the cam shaft has rotated through about 255 degrees from its starting position and then commences to move in the opposite direction and moves in the latter direction, between the points marked *a* and *b* in line C in the diagram, while the cam shaft rotates through about a further 80 degrees when it commences to again move in the direction of feed. The awl is moving in the direction of work feed at the commencement of the machine cycle, see the line D in the diagram and continues to move in this direction while the cam shaft rotates through about 55 degrees from its starting position. The awl then moves in

the opposite direction, between the points marked *a* and *b* in line D in the diagram, while the cam shaft rotates through about a further 100 degrees and then moves in the opposite direction until the end of the cycle.

The channel guide is moving in the direction of feed, see the line E in the diagram, at the commencement of the cycle and continues to move in that direction during about 55 degrees of rotation of the cam shaft from its starting position. The channel guide then commences to move in the opposite direction and continues to do so during about a further 100 degrees of rotation of the cam shaft when it again begins to move in the direction of feed. The channel guide moves again in the direction of feed during about a further 100 degrees of rotation of the cam shaft and then again moves in the opposite direction while the cam shaft rotates through about 80 degrees when the channel guide commences to once more move in the direction of feed and so moves until the end of the cycle. It will, therefore, be apparent that during each cycle of the machine the channel guide moves to and fro twice, the channel guide therefore acting to feed or assist in feeding the work twice in each cycle.

During about the first 55 degrees of rotation of the cam shaft in each cycle of the machine, the awl, needle and channel guide are moving together in the direction of feed, and the needle and channel guide are feeding the work. During about the next 100 degrees of rotation of the cam shaft, the needle alone continues to feed the work and the awl and channel guide move back in the opposite direction. During about the next 100 degrees of rotation of the cam shaft the awl, needle and channel guide all move in the direction of feed, the awl and channel guide actually feeding the work. During about the next 80 degrees of rotation of the cam shaft, the awl alone is feeding the work, and the needle and channel guide are moving in the opposite direction and during about the last 25 degrees of rotation of the cam shaft the awl, needle and channel guide are all moving in the direction of feed.

The illustrative machine includes a welt guide 215 for guiding a welt to a shoe to which the welt is being sewn, for which the usual form of back gage may be substituted when a turn shoe is to be sewn as is customary in inseam shoe sewing machines. The welt guide is secured to the lower end of an upwardly extending welt guide arm 217 and consists of a more or less horizontal loop of thin metal, the arms of which extend rearwardly and are secured to the arm. The loop has in it a gauge which may be adjusted forwardly or rearwardly to suit the width of the welt being used. The welt guide is positioned behind the channel guide 5 and moves to and fro with the awl 1 during its feeding and return movements. The welt guide arm is curved from its lower end upwardly and forwardly to a comparatively long horizontal hub 219 (Figure 8) of a welt guide arm 217 from which it extends, extending laterally of the machine. The hub 219 of the welt guide lever is pivotally mounted on an eccentric portion 221 of a horizontal spindle 223 extending laterally of the machine. The left hand end of the spindle 223 is slidably mounted in the bracket 63 at the front of the head of the machine and the hub 219 of the welt guide lever 217 is constrained to move laterally with the spindle by a shoulder

at the left hand end of the spindle at one end of the eccentric portion thereof and a sleeve 225 secured in a reduced threaded concentric portion 227 at the other end of the spindle. The sleeve 225 passes through a bore in a small block 229 and the reduced portion 227 has at the right of the block 229 a nut 231 by which the block may be clamped to the spindle. The sleeve 225 is slidably mounted in the aforesaid bracket 19. 5 The small block 229 is guided in and prevented from rotating by guideways in the right hand bracket 19 which are engaged by rearwardly and forwardly projecting portions 233, 235 of the block (Figures 1 and 6). If the nut 231 on the right hand end of the spindle is slackened, the spindle may be rotated to adjust the welt guide upwardly or downwardly relatively to the awl. The rearwardly extending portion 233 (Figure 6) of the small block 229 has extending through it 10 a vertical stud 237 on which is pivoted the forked right hand end of a link 239 which extends towards the left, and the left hand end of the link 239 is pivoted on the same stud 151 as the left hand end of the link 149 associated with the awl feed mechanism so that the welt guide moves laterally to and fro with the awl and the welt guide may therefore be positioned close to the right hand side of the awl with the result that the welt is accurately guided into the path of the awl. The welt is moved towards 15 and from the work twice during each cycle of the machine. The welt guide is locked against rearward movement during the greater part of the machine cycle, being unlocked only when it is moving towards the work. The welt guide is moved forwardly into engagement with the shoe by a spring so that the welt guide can accommodate itself to the position forwardly or rearwardly of the machine of the portion of the shoe which it engages.

The hub 219 of the welt guide lever has an arm 241 (Figures 1 and 4) extending upwardly and forwardly from it. The upper end of the arm 241 has connected to it by a universal coupling the lower end of an upwardly and rearwardly extending rod 243 and has also connected to it the lower end of a spring 245, which moves the welt guide forwardly, which extends upwardly and rearwardly and at its upper end is connected to a pin 247 extending laterally from an arm 249 adjustably secured on a horizontal shaft 251 extending laterally of and secured in the machine head. The arm 249 may be adjusted about its shaft 251 to adjust the tension of the spring 245. The upper end of the rod 243 is 20 pivotally connected to a horizontal pin 253 (Figure 10) extending laterally of the machine, the pin 253 being slightly smaller than the bore in the rod 243 so that the forward end of the latter can move laterally of the machine with the welt guide. The pin 253 is carried by part of a welt guide locking and actuating mechanism similar in many respects to the presser-foot locking and lifting mechanism disclosed in Patent No. 2,056,670 dated October 6, 1936. The pin 253 is carried by the middle portion of a short link 255 which extends upwardly and forwardly in the machine. The upper end of the short link 255 is pivotally connected by a horizontal pin 257 extending laterally of the machine to the forward end of a rearwardly and upwardly extending rod 259. The rod 259 at its upper end is pivotally mounted on a horizontal stud 261 extending laterally of the machine which is adjustably secured in an arcuate slot

263 formed in one arm 265 of a cam lever 267 which is pivoted on a horizontal shaft 269 secured in the machine head. Another arm 271 (Figures 1 and 2) of the cam lever 267 carries a cam roll 273 which engages in a cam groove formed in a cam on the cam shaft 29.

By adjusting the stud 261 along the arcuate slot 263 in the cam lever, the position to which the welt guide is moved rearwardly by the cam lever may be varied. The lower end of the aforesaid short link 255 is pivotally connected by a horizontal pin 275 (Figures 10 and 11) extending laterally of the machine, to a pair of wedge plates 277, 279 and a central wedge member 281 which are slidably mounted in a block 283 which is secured to the machine head 21. The holes in the wedge plates and central wedge member are slightly larger than the diameter of the pin for the reason described in said patent. Between the wedge plate 279 and the central wedge member 281 is a spacing piece 285 and between the other wedge plate 277 and the central wedge member 281 are a series of steel rollers 287. The series of rollers 287 is engaged at one end by a tapered bar 289 which is adjustably mounted on the machine head 21. The other end of the series of rollers 287 is engaged by a locking finger 291 which extends upwardly and forwardly from a hub 293 rotatably mounted on a horizontal shaft 295 extending laterally of the machine and secured in the machine head 21. The hub 293 of the locking finger has extending from it a sleeve portion 294 (Figure 12) on which is mounted a cam arm 297 (Figures 1, 2 and 10) having extending from it a cam roll 299 which engages in a cam on the cam shaft 29. The hub 293 has in it a spring plunger 301 arranged to normally engage a recess in the cam arm 297 and cause the cam arm 297 and finger 291 to normally move together. The plunger 301 allows the cam arm 297 to move relatively to the finger 291 after the latter has pressed the rollers 287 into locking engagement with the plate 277 and central wedge member 281.

The welt guide, as has already been stated, moves to and fro with the awl. The welt guide is in engagement with the work during about all the time when the awl, needle and channel guide are all moving in the direction of feed as hereinbefore described and is withdrawn from engagement with the work during those times in the machine cycle when the needle and channel guide and the awl and channel guide are moving in the opposite direction. The welt guide is unlocked during those times when it is moving forwardly into engagement with the work so that it can accommodate itself to the position in the machine of that face of the work which it engages.

The illustrative machine includes a thread deflector 303 (Figures 1, 4 and 13) operating to deflect the loop of thread drawn back by the needle substantially as described in applicants' pending application hereinbefore referred to.

The thread deflector 303 in the illustrative machine is given a different movement to that described in said application in order to cooperate with the devices for feeding the work continuously.

In the illustrative machine the needle after it has drawn a loop of thread through the work and has reached its most rearward position moves towards the right in the opposite direction to the feed of the work and the thread deflector 303 is caused to move with the needle so that

the needle does not exert an undesirable strain on the thread engaged by the deflector during such movement of the needle. The thread deflector in the illustrative machine engages and deflects the loop of thread extending from the work to the needle as the latter is moving rearwardly and retains its engagement with the loop during movement of the needle towards the work. The loop deflector then moves downwardly and rearwardly at the left of the needle, below the level of the needle, to release the loop and is moved to the right of the needle before it is moved upwardly and forwardly in readiness to engage the next loop drawn through the work by the needle before it is moved to the left to deflect that loop.

In the illustrative machine, the deflector 303 is secured in a member 305 pivoted by pins 307, 309 (Figure 13) to a pair of parallel links 311, 313 which are pivoted at 315, 317 to a cam lever 319 (Figures 1 and 2) which is pivoted on a horizontal stud 321 extending laterally of the machine and secured in the head 21 of the machine. The cam lever carries a cam roll 323 which enters a cam groove in a cam on the cam shaft 29 of the machine. The link 313 has a rearwardly extending arm 325 to which is connected by a universal coupling the right hand end of a rod 327. The left hand end of the rod 327 is connected by a universal coupling to one arm 329 of a cam lever 341 which is pivoted on a forwardly and upwardly extending shaft 343 secured in the head of the machine. Another arm 345 of the cam lever 341 carries a cam roll 347 which engages in a cam groove in a cam on the cam shaft 29. The cam levers 319, 341 move the thread deflector 303 forwardly and rearwardly about the shaft 321 and laterally about the shaft 343.

However, in the illustrative machine, the deflector may be connected to the welt guide and be caused to move lengthwise in the member, instead of being secured thereto, towards and from the work with the welt guide. This latter arrangement ensures that the deflector engages the thread a uniform distance away from the work irrespective of the position in the machine forwardly and rearwardly thereof of the face of the work which the welt guide engages.

If the thread deflector is connected to the welt guide so as to move forwardly and rearwardly with the guide, the deflector is secured in a sleeve 348 (Figure 14) slidably mounted in the aforesaid member 305 instead of being secured in the member, and the upper end of the deflector has formed in it a forwardly and rearwardly extending recess which receives the rear rounded end of one arm 349 of a bell-crank lever 351 pivoted on a horizontal pivot 353 extending laterally of the machine secured in the aforesaid member 305 in which the deflector is slidably mounted. Another arm 355 of the bell-crank lever 351 extends upwardly from the hub of the lever and its upper end is connected by a universal coupling to the rear end of a forwardly and upwardly extending rod 357. The forward end of the latter rod 357 is connected by a universal coupling to the upper end of an arm 359 extending from the aforesaid hub 219 of the welt guide lever.

The illustrative machine includes a looper 361 and a thread finger 363.

The thread finger 363 has a forked lower end for engaging the thread and from its lower end the thread finger extends upwardly. From the upper end of the thread finger there extends a stem 365 (Figure 1) which is rotatably mounted

in the machine head. The forward end of the stem 365 has secured on it an arm 367 to which is pivotally connected the lower end of a link 369. The upper end of the link 369 is pivotally connected to an arm 371 of a cam lever which is secured on a shaft 373 which is rotatably mounted in a bracket 375 secured on the machine head. Another arm 377 of the cam lever carries a cam roll which engages in a cam groove in a cam on the cam shaft 29.

In the illustrative machine the looper 361 (Figure 1) extends upwardly and forwardly from its lower end, i. e., the end from which the thread emerges, and is secured in the lower end of one arm 379 of a looper lever 381 which also extends upwardly and forwardly of the machine. The looper lever 381 has secured in it about mid-way of its length a more or less horizontal stud 383 extending laterally of the machine which is rotatably mounted in a block 385 pivoted on an upwardly and rearwardly extending pivot 387 secured in the machine head. Another arm 389 of the looper lever 381 extends upwardly and forwardly from the hub of the lever and at its upper end is connected by a universal coupling to the forward end of a guiding lever 391 (Figures 1, 4 and 15) which extends upwardly and rearwardly from its lower end more or less at right angles to the looper lever and is pivoted about mid-way of its length on a downwardly and rearwardly extending pivot 393 secured in an arm 395 which is pivoted at the right hand side of the guiding lever 391 on a downwardly and rearwardly extending pivot 397 secured in the machine head. The upper end of the guiding lever 391 is pivotally connected by a downwardly and rearwardly extending pivot 399 to the lower ends of a pair of links 401, 403 one extending upwardly and towards the right from its lower end, and the other extending upwardly and towards the left. The upper ends of the links 401, 403 are each pivotally connected to cam levers 405, 407 which are actuated by a cam on the cam shaft 29. The cam levers 405, 407 are pivoted on the same downwardly and rearwardly extending pivot 409 which is secured in the machine head. This mechanism causes the lower end of the looper to move in a closed path around the end portion of the needle when the latter is projecting forwardly through the work to lay the thread in the hook of the needle. When wrapping the thread around the needle, the looper, i. e., its lower end, moves from a position at the left hand side and somewhat rearwardly of the needle, where the thread finger can engage the thread extending from the looper to the work, forwardly and around the front of the needle to a position directly behind the path of the needle, the needle having moved rearwardly somewhat with the thread laid in its hook. The looper dwells in this position, while the thread finger returns to the left, having moved to the right to assist in laying the thread in the hook of the needle, and then moves rearwardly and to the left into its starting position. It will be noted that by reason of the manner in which the looper lever 381 is mounted, the looper 361 may be moved in any desired path and it will also be noted that the mechanism for actuating the looper lever comprising the guiding lever 391 (see Fig. 15), the swinging arm 395 on which the guiding lever is pivotally mounted, the cam levers 405, 407 and the links 401, 403 connecting the cam levers to one end of the guiding lever 391 permit the

looper 361 to be moved about the needle and properly thread the needle, notwithstanding the movement of the needle in the direction of feed while being looped.

5 The cam shaft 29 of the illustrative machine is driven in the reverse direction, to that in which it is driven during normal operation of the machine, during the stopping of the machine, and during such reversal of the cam shaft the welt guide is moved rearwardly and the channel guide is moved forwardly so as to allow the work to be readily removed.

The illustrative machine includes a clutch and reverse driving mechanism substantially similar to that described in the patent to Topham No. 1,099,326 dated June 9, 1914, and includes an actuating lever 411 (Figure 2) which actuates the actuating lever. The actuating lever 411 is pivoted to the upper end of an arm 415 of a bell-crank lever 417 which is pivoted on a horizontal shaft 419 extending laterally of the machine and secured in the machine head rearward of and lower than the cam shaft. The other arm 421 of the bell-crank lever 417 extends forwardly beneath the cam shaft. During the reverse rotation of the cam shaft during the stopping of the machine after a clutch controlling treadle thereof has been released, the bell-crank lever 417 is moved by the actuating lever 411 in a clockwise direction viewed from the right to raise a shoulder 423 on the forwardly extending arm 421 of the bell-crank lever into the path of a stop face 425 on a cam on the cam shaft, and the engagement of the stop face with the shoulder 423 stops the reverse rotation of the cam shaft. The upper end of the aforesaid arm 415 of the bell-crank lever 417 has rotatably mounted in it a horizontal pivot 427 extending laterally of the machine which has pivoted on it the aforesaid actuating lever 411. The pivot 427 has on it an eccentric portion (not shown) to which is connected one end of a brake band extending partly around the periphery of a cam on the cam shaft, the other end of the brake band being secured to the head of the machine. The pivot 427 has secured on it a treadle controlled lever 429 having a forwardly and downwardly extending arm which is connected by a downwardly extending rod 431 to the aforesaid clutch controlling treadle. The treadle controlled lever 429 has extending rearwardly from it a rearwardly extending arm 433 having secured to its underside a hardened plate 435. When the treadle is released, the treadle rod 431 is raised by a spring 55 and the treadle controlled lever 429 is thereby rotated in a clockwise direction, viewed from the right, and the hardened plate 435 is moved downwardly into such a position that when the aforesaid arm 415 of the bell-crank lever 417 on which 60 the treadle controlled lever is pivoted is moved in a clockwise direction when viewed from the right, i. e., rearwardly, it engages a pin 437 projecting laterally from the lower end of a depending arm 439 of a welt guide operating lever, 65 which arm is secured on a horizontal shaft 441 extending laterally of the machine and is rotatably mounted in a bearing at the rear of the machine head and moves this arm in an anti-clockwise direction.

70 Another arm 443 secured on the shaft 441 and forming part of the welt guide operating lever extending upwardly and has pivotally connected to its upper end by a horizontal pivot extending laterally of the machine, the rear end of a forwardly extending link 445. The forward end of

the link 445 is pivotally connected to one arm of a bell-crank lever 447 which is pivoted on a horizontal shaft 449 extending laterally of the machine and secured in the machine head. The other arm of the bell-crank lever 447 is connected to the upper end of a downwardly and forwardly extending link 451 by a pin in the arm and a slot extending lengthwise of the link. The lower end of the link 451 is pivotally connected by a horizontal pin extending laterally of the machine to the upper ends of the aforesaid wedge plates 277, 279 (Figure 11) associated with the welt guide locking mechanism and when, as the machine comes to rest, the welt guide operating lever is swung in an anti-clockwise direction the welt guide is moved rearwardly.

The aforesaid vertical shaft 183 on an eccentric portion 181 of which the channel guide lever 179 is pivoted may be rotated to adjust the channel guide forwardly or rearwardly and then locked in position.

Just before the machine comes to rest during reverse rotation of the cam shaft 29, the actuating lever 411 is moved rearwardly and swings the bell-crank lever 417 to which it is connected in a clockwise direction viewed from the right. The treadle will have been released and raised by a spring connected to it and to the machine frame. As the treadle is raised, the treadle controlled lever 429 is swung in a clockwise direction and moves the block 435 carried by it downwardly into a position where it can engage the pin 437 in the welt guide operating lever 439, 443 when as aforesaid, the bell-crank lever 417 to which the actuating lever 411 is connected is swung in a clockwise direction as the machine comes to rest.

When, just before the machine comes to rest, the bell-crank lever 417 to which the actuating lever 411 is connected is moved in a clockwise direction, viewed from the right, the welt guide operating lever 439, 443 is swung in a counter-clockwise direction by the engagement of the block 435, on the treadle controlled lever 429 with the pin 437 in a downwardly extending arm 439 of the welt guide operating lever and the welt guide is moved rearwardly. The arm 421 on the bell-crank lever 417 to which the actuating lever 411 is connected and which extends forwardly beneath the cam shaft has pivotally connected to its forward end the lower end of an upwardly extending rod 453. The upper end of the rod 453 has in it a slot through which passes a pin 455 extending laterally from an arm 457 (Figures 10 and 12) extending rearwardly from the hub 293 of the locking finger 291 of the welt guide locking mechanism. When just before the machine comes to rest the bell-crank lever 417 to which the actuating lever 411 is connected is swung in a clockwise direction, the arm 421 of the bell-crank lever which extends beneath the cam shaft is raised and through the rod 453 unlocks the welt guide, which is locked at this time in the cycle of the machine during its normal operation, the unlocking of the welt guide occurring just before it is moved rearwardly during the stopping of the machine as hereinbefore described.

The spring plunger 301 enables the arm of the bell-crank lever 421 to which the rod 453 is connected to move upwardly after the welt guide is unlocked and the slot at the upper end of the rod allows the locking finger to be operated during normal operation of the machine to lock and unlock the welt guide. It will, therefore, be ap-

parent that just before the machine comes to rest the welt guide is moved rearwardly so that the work may conveniently be removed from the machine and a fresh workpiece may be presented thereto.

When the treadle is depressed to cause the machine to operate, the block 435 on the treadle controlled lever 429 is immediately raised above the pin 437 in the welt guide operating lever and allows the welt guide to be moved forwardly by its spring 245. Also, as the treadle is depressed the brake band is released owing to the aforesaid pivot, in the upwardly extending arm 415 of the bell-crank lever to which the actuating lever 411 is connected, which has on it the eccentric portion to which one end of the brake band is connected being rotated.

The relative timing of many of the operating parts of the machine has already been indicated. The exact timing of these and the remaining operating parts of the machine will be readily understood without further description from an inspection of the timing diagram illustrated in Figure 23 in which the line A indicates the forward and rearward movements of the awl, the line B indicates the forward and rearward movements of the needle, the line C indicates the feeding and back-feeding movements of the needle, the line D indicates the feeding and backing movements of the awl, the line E indicates the movements of the channel guide, the line F indicates the movements of the thread finger, the lines G and H indicate the movements of the deflector, the lines I and J indicate the movements of the looper, the line K indicates the movements of the take-up, the line L indicates the backward and forward movements of the welt guide, and the line M indicates the locking and unlocking of the welt guide.

The nature and scope of the invention having been indicated, and a machine embodying the several features of the invention having been specifically described, what is claimed is:

1. A chainstitch inseam shoe sewing machine having, in combination, stitch-forming and work feeding devices including a curved hook needle operating to draw a loop of thread through the work and through a previously formed loop, means for actuating the stitch-forming and work feeding devices to impart a continuous feeding movement to the work, a loop deflector, and means for imparting movement to the deflector and needle relative to each other while the needle is out of the work to deflect the loop carried by the needle towards the previously formed stitches.

2. A chainstitch inseam shoe sewing machine having, in combination, stitch-forming and work feeding devices including a curved hook needle operating to draw a loop of thread through the work and through a previously formed loop, means for actuating the stitch-forming and work feeding devices to impart a continuous feeding movement to the work including means for moving the needle with the work while in engagement therewith, a loop deflector, and means for actuating the deflector while the needle is out of the work to deflect the loop carried by the needle towards the previously formed stitches, and thereafter to move with the needle during the back-feeding movement of the needle.

3. A chainstitch inseam shoe sewing machine having, in combination, stitch-forming and work feeding devices including a curved hook needle operating to draw a loop of thread through the work and through a previously formed loop,

means for actuating the stitch-forming and work feeding devices to impart a continuous feeding movement to the work including means for moving the needle with the work while in engagement therewith, a loop deflector, and means for moving the deflector transversely to the line of feed into and out of engagement with the loop carried by the needle and, while in engagement with the loop, for moving the deflector to deflect the loop towards the previously formed stitches and thereafter move with the needle during the back-feeding movement of the needle.

4. A chainstitch inseam shoe sewing machine having, in combination, stitch-forming and work feeding devices including a curved hook needle operating to draw a loop of thread through the work and through a previously formed loop, means for actuating the stitch-forming and work feeding devices to impart a continuous feeding movement to the work, a welt guide, means for yieldingly forcing the welt guide against the shoe, a loop deflector, a connection between the loop deflector and the welt guide to regulate the distance of the deflector from the shoe, and means for imparting movement to the deflector and needle relative to each other while the needle is out of the work to deflect the loop carried by the needle towards the previously formed stitches.

5. A chainstitch inseam shoe sewing machine having, in combination, stitch-forming and work feeding devices including a curved hook needle operating to draw a loop of thread through the work and through a previously formed loop, means for actuating the stitch-forming and work feeding devices to impart a continuous feeding movement to the work including means for moving the needle with the work while in engagement therewith, a loop deflector, and means for actuating the deflector while the needle is out of the work to deflect the loop carried by the needle towards the previously formed stitches, thereafter to move with the needle during the back feeding movement of the needle and to remain in engagement with the loop during the movement of the needle towards the work.

6. A chainstitch inseam shoe sewing machine having, in combination, stitch-forming and work feeding devices including a curved hook needle operating to draw a loop of thread through the work and through a previously formed loop, a welt guide, mechanism for moving the welt guide towards and from the shoe during each stitch-forming cycle, a loop deflector, lever and link connections between the welt guide moving mechanism and the deflector to regulate the distance of the deflector from the shoe, and means for actuating the deflector while the needle is out of the work to deflect the loop carried by the needle towards the previously formed stitches.

7. An inseam shoe sewing machine having, in combination, stitch-forming and work feeding devices comprising a curved hook needle, a channel guide and an awl, and means for moving the channel guide, needle, and awl back and forth in the line of feed to impart a continuous feeding movement to the work acting to move the channel guide back and forth in the line of feed a plurality of times during each stitch-forming cycle.

8. An inseam shoe sewing machine having, in combination, stitch-forming and work feeding devices comprising a curved hook needle, a chan-

nel guide and an awl, means for moving the needle, awl, and channel guide back and forth in the line of feed to feed the work, acting during each stitch-forming cycle to back feed the channel guide with the awl while the needle is feeding the work and to again back feed the channel guide while the awl is feeding the work.

9. An inseam shoe sewing machine having, in combination, stitch-forming and work feeding devices comprising a curved hook needle, a channel guide and an awl, and means for actuating said devices to impart a continuous feeding movement to the work acting to cause the awl to impart a faster feeding movement to the work than the needle as the needle enters the work.

10. An inseam shoe sewing machine having, in combination, stitch-forming and work feeding devices comprising a curved hook needle, a channel guide and an awl, separate carriers for the needle and awl, cams and suitable connections for moving the carriers back and forth in the line of feed to feed the work, and mechanism actuated by said connections for moving the channel guide back and forth in the line of feed twice during each stitch-forming cycle.

11. An inseam shoe sewing machine having, in combination, stitch-forming and work feeding devices comprising a curved hook needle, a channel guide and an awl, separate carriers for the needle and awl, cams and suitable connections for moving the carriers back and forth in the line of feed to feed the work, and mechanism for moving the channel guide back and forth in the line of feed comprising a lever, a connection from the awl actuating connections to one end of the lever, a connection from the needle actuating connections to the other end of the lever, and a member connected to the channel guide on which said lever is pivotally mounted intermediate its ends, and which is actuated to move the channel guide by the bodily movement of the pivot of the lever.

12. An inseam shoe sewing machine having, in combination, stitch-forming and work feeding devices comprising a curved hook needle, and an awl, separate carriers for the needle and awl, cams and suitable connections for moving the carriers back and forth in the line of feed, a welt guide, a separate carrier for the welt guide, and connections from the awl actuating connections to the welt guide carrier for moving the welt guide carrier with the awl carrier back and forth in the line of feed.

13. An inseam shoe sewing machine having, in combination, stitch-forming and work feeding devices comprising a curved hook needle, a channel guide and an awl, means for moving the needle, awl, and channel guide back and forth in the line of feed to impart a continuous feeding movement to the work comprising means for moving the channel guide back and forth twice during each stitch-forming cycle, a welt guide movable towards and from the work, and means for moving the welt guide away from the work twice during each stitch-forming cycle to relieve the pressure on the work during the back-feeding movements of the channel guide.

14. An inseam shoe sewing machine having, in combination, stitch-forming devices including a curved hook needle, a welt guide movable towards and from the shoe, mechanism for actuating the welt guide comprising a pivoted lever, connections between the lever and the welt guide, a movable support for the fulcrum of the lever, a cam, and connections from the cam to

the lever for moving the lever about its fulcrum to move the welt guide away from the work while the fulcrum support is locked, means for locking and unlocking the fulcrum support during each stitch-forming cycle, and a spring acting on the connections between the lever and the welt guide while the fulcrum support is unlocked to move the welt guide towards the shoe.

15. An inseam shoe sewing machine having, in combination, stitch-forming devices including a curved hook needle, a welt guide movable towards and from the shoe, mechanism for actuating the welt guide comprising a pivoted lever, connections between the lever and the welt guide, a movable support for the fulcrum of the lever, a cam, and connections from the cam to the lever for moving the lever about its fulcrum to move the welt guide away from the work while the fulcrum support is locked, means for locking and unlocking the fulcrum support during each stitch-forming cycle, means for yieldingly moving the welt guide towards the shoe while the fulcrum support is unlocked, and means operating on stopping the machine to unlock the fulcrum support and move the welt guide away from the shoe.

16. An inseam shoe sewing machine having, in combination, stitch-forming and work feeding devices including a curved hook needle and a curved awl arranged to enter the work from the upper side of the shoe, oscillating carriers for the needle and awl, and means for supporting the awl carrier to cause the awl during its oscillating movements to move in a plane angularly disposed with relation to the plane of movement of the needle.

17. An inseam shoe sewing machine having, in combination, stitch-forming and work feed-

ing devices including a curved hook needle and a curved awl arranged to enter the work from the upper side of the shoe, oscillating carriers for the needle and awl, and a bracket upon which the awl carrier is supported, and means for adjusting said bracket to cause the awl during its oscillating movements to move in a plane angularly disposed with relation to the plane of movement of the needle.

18. A shoe sewing machine having, in combination, stitch-forming devices including a hook needle and a looper for threading the needle, and means for actuating the looper to carry the thread about the needle comprising a lever pivotally mounted to swing about its pivot and move bodily longitudinally, connections from one end of the lever to the looper, a pair of links pivotally connected to the other end of the lever, and cam actuated levers connected to the links, said cam actuated levers and links cooperating to impart longitudinal and swinging movements to said first-mentioned lever.

19. A shoe sewing machine having, in combination, stitch-forming devices including a hook needle and a looper for threading the needle, and means for actuating the looper to carry the thread about the needle comprising a lever, a pivotally mounted arm upon which the lever is pivotally mounted intermediate its ends, connections from one end of the lever to the looper, a pair of links connected to the other end of the lever, cam actuated levers connected to the links, said cam actuated levers and links cooperating to swing said first mentioned lever about the pivotal connection with its supporting arm and to swing the supporting arm about its pivot.
